UNITED STATES PATENT OFFICE.

SARAH R. MILLS, OF SAN FRANCISCO, CALIFORNIA.

CORSET-FASTENER.

SPECIFICATION forming part of Letters Patent No. 630,389, dated August 8, 1899.

Application filed December 6, 1898. Serial No. 698,470. (No model.)

To all whom it may concern:

Be it known that I, SARAH R. MILLS, a citizen of the United States, residing at San Francisco, in the county of San Francisco and 5 State of California, have invented certain new and useful Improvements in Corset-Fasteners, of which the following is a specification.

My invention relates to improvements in 10 corset-fasteners, the object of my invention being to provide a device of this character which will avoid injury to the dress worn over the corset, such as is caused by the fasteners at present in use; and a further object of my 15 invention has been to provide a simple and inexpensive corset-fastener which shall also serve as a means for holding the corset-laces in position when tied.

Corset-fasteners as at present devised and 20 used, so far as my knowledge extends, consist of a loop or eye attached to one corset-steel and a stud projecting from the other corset-steel through the fabric of the corset and engaged by said eye or loop. The part 25 of the dress immediately below the waist is usually worn tight around the form, and the consequence is that the studs in the lower part of the corset, projecting above its surface and against which the dress presses with con- 30 siderable force, indent, deform, and abrade each a small portion of the dress immediately above it. The effects of this continual pressure and abrasion are very soon visible from the outside, and the dress is quickly worn out 35 at this place and must be cast aside or repaired. The dress may be repaired by inserting a piece of the goods in the place of the part that has had holes worn through by the studs; but this remedy is troublesome, expen- 40 sive, and unsatisfactory, the result being a patched-up garment, and, moreover, it is sometimes impracticable on account of the goods being exhausted in the store.

The object of my invention has been to 45 avoid this annoyance and expense.

My invention further resides in the novel construction, combination, and arrangement of the parts hereinafter fully specified, and more particularly pointed out in the claims.

50 In the accompanying drawings, Figure 1 is a front elevation of the marginal portions of a corset furnished with my improved fas-

tener and shown as fastened thereby. Fig. 2 is a similar view of the lower portion only of the corset-steels, the cloth covering being 55 removed and the steels being shown as separated. Fig. 3 is an enlarged horizontal section on the line 3 3 of Fig. 1 and Fig. 4 is a perspective view of the lowest fastener in the corset, showing the device for holding the 60 corset-laces in position.

1 and 2 represent the two sides of the corset, provided with the steels 3 4, respectively. The upper portions of the steels 3 4 have secured thereon the eyes 5 and studs 6, respectively, said eyes and studs being of the usual construction. This fastening device is not objectionable in the upper part of the corset, for the reason that the dress is not drawn tight over the juncture of the halves of the 70 corset in its upper portion. Over the lower part of the corset, however, the dress is frequently worn quite tight, and for the purposes hereinbefore explained I provide in said lower portion on one steel 3 a hook 7, made 75 of a piece of sheet metal bent around and behind the edge of the corset-steel and engaging a square-shaped loop 8 on the other steel 4, said loop being also made of a flat piece of metal. Said hook 7 and loop 8 are 80 secured by rivets 9, the loop 8 preferably on the under side of the steel and the hook 7 on the upper side of its steel, as shown; but this arrangement may be varied without seriously diminishing the advantages of the 85 device, for any inequalities of the surface will be sufficiently covered by the fabric of the corset. Thus I provide a device which fastens the two halves of the corset together in such a manner that the fastening is located 90 entirely below the surface of the corset, so that there are no projecting points to abrade and unduly wear out the dress.

The loop 8 at the bottom of the corset has integrally formed thereon a downwardly-extending tongue 10, which, it will be seen, finds its place between the corset-steels when the hook 7 and loop 8 are united. This tongue 10 will be found to be very convenient for holding the corset-laces in position, the latter being brought around from the back of the corset underneath the said tongue and tied in front.

I am aware that it has been common to se-

cure a hook at the bottom of the corset for the purpose of holding the laces in position; but these hooks are inferior to the device herein described in the following respects: 5 first, they have had to be attached on one or the other of the corset-steels, so that the laces secured thereunder have not been symmetrically disposed, this unsymmetrical arrangement showing in the ridges in the dress, 10 whereas with my device the tongue is precisely in the middle of the corset; secondly, said hooks have projected above the surface of the corset, abrading the dress in the same manner as do the studs in common use in 15 corset-fastenings, and, thirdly, they have been formed in a separate piece, requiring a separate attachment to the corset, and therefore considerable additional expense and trouble, whereas the tongue 10, being formed 20 integral with the loop 8, requires no separate attachment and substantially no extra expense.

I claim—

1. A corset having in its upper portion hooks on one steel and eyes on the other steel 25 engaging above the surfaces of the steels, and, near the margin of the lower portion a hook on one steel and an eye on the other steel engaging below the surfaces of the steels, substantially as described.

2. A corset having a hook on one steel, and an engaging loop on the other steel, said loop having formed integrally therewith a downwardly-extending tongue, located between the two steels when the hook and loop are 30 35 engaged, substantially as described.

In witness whereof I have hereunto set my hand in the presence of two subscribing witnesses.

SARAH R. MILLS.
